UNITED STATES PATENT OFFICE.

PETER J. McINERNEY, OF DALLAS, TEXAS.

GROOVING AND REINFORCEMENT SUPPORTING DEVICE AND PROCESS.

Application filed January 29, 1925. Serial No. 5,539.

REISSUED

This invention relates to a device and process for mechanically placing joints, parting lines, patterns, markings and designs in plastic and semi-solid substances such as 5 asphalt, concrete or other matrices, referring more particularly to a device of this character for making cleavage planes in highways, pavements, walks, roofs, floors or other construction of a like nature, and at 10 the same time positioning reenforcement means in said construction, where expansion or contraction occurs after the material has mechanically set.

An object of the invention being the provision of a device which will mark or cleave the matrice, so that when possible separation of the latter takes place, such separation will occur along the cleavage plane.

An object is to provide a device which 20 will be easily adjustable to form demarkations of different depths and widths.

Another object is to provide such a device that will form said cleavage plane, before the material has attained a mechanical set.

25 A further object is to provide a device which will place or position suitable reinforcement as the demarkation is made.

An advantage or feature of the invention is its simplicity of construction and economy 30 of operation.

A further feature is the almost entire elimination of destructive and unsightly fissures or cracks, separation, if present, occurring along the cleavage plane or planes 35 made by the invention.

A feature of importance is that the blade or cutting member of the device will form an opening in the matrice which will allow settlement deflection of the material without 40 buckling or rupturing the structure.

A still further feature of the device is that it is so operated that a jointed band or ribbon of suitable material may pass through 45 the blade, which is hollow, and remain permanently in the fissure formed by the blade, or may be taken up and used again after the matrice has set.

Also, hinge action of the blocks or sections 50 of the matrice, is permitted by the use of the device.

The cleavage planes formed by the device permit the placing of struts or other reenforcement below the cleavage planes or parting planes.

55 And the device may be used without em-

ploying the jointed tape or ribbon, the cleavage planes being made by the blade of the device, and then filled with material of consistency and color different than the matrice.

These objects together with advantages and features of the invention may be more readily understood by reference to the following description, of which the annexed drawings form a part, and in which:

Figure 1 represents a plan view of the invention in attachment to a concrete mixer.

Figure 2 shows a side elevation of the invention, partly in section.

Figure 3 is a cross-sectional view taken 70 on lines 3-3 in Figure 2.

Figure 4 is a cross section taken on lines 4-4 in Figure 2.

Figure 5 is a perspective view of the invention on a highway.

Figures 6, 7, 8, 9, 10, 11, and 12, represent different grooves or demarkations that are possible with the device.

Figure 13 is a cross-section on lines 13-13 in Figure 2.

Continuing the description, a concrete mixer 1 of the portable type is shown in Figure 1 on a highway or pavement or other like surface marked by side forms 2-2.

This mixer is attached to a subgrade template 3 which moves along the forms 2-2 on wheels 5-5, journaled on shafts 6-6, which are set in each end of the template. The template is attached to the concrete mixer by chains 4-4, or other suitable means, and moves forward with the mixer.

A rod 9 extends parallel with the template and is likewise supported with wheels or rollers 8-8, moving on the side forms. Ties 7-7 hold the wheels on the rod and the wheels 90 on the template in rigid relationship, maintaining the rod and template parallel. A blade 11 of steel and preferably of hollow construction, is secured to the template and supported by the rod. Braces 10-10 hold it rigid in attachment to the template. A spool 13 is mounted on a shaft 13^a adjacent the point of attachment of the blade and template, and a jointed tape 12 is wound on this spool and passes therefrom over a guide roller mounted to rotate freely on shaft 14^a.

This shaft is positioned adjacent the end of the blade. The tape or ribbon, over the guide roller 14 extends through the blade 110 to the other end thereof. Its operation will 105

be described more fully hereinafter. The numeral 15 designates the point of attachment of the blade to the template.

In Figures 2 and 5, the details of construction of the blade are more clearly shown, and also the position of the blade in relation to the subgrade 19 and the matrice or surfacing 20. It will be noted that the blade, though shown in the drawings with its upper edge 10 flush with the finished matrice surface, may be below the surface, the finisher 16 operating however above the blade the latter is not adapted to protrude above the finished surface. As the mixer is moved forward the 15 blade cuts the groove or channel and the tape passing through the blade is deposited in the channel or groove as the same is formed, or if the blade is used without the tape, the cleavage may be filled with resilient material 20 suitable and in common use as a filler of this character. T members or runners 21 in attachment to the template extend longitudinally with the blade and as the device moves forward, pass from under reenforcements 25 22-22, leaving them positioned below the groove or demarkation.

The opening or tunneling in the blade is designated by letter α .

The upright or body portion of the template is designated by numeral 18, and the subgrade shoe in Figure 3 by numeral 3^a. The blade is formed by steel plates joined together at the tops on plate 17 set between them and are welded together at their bottoms.

In the figures showing the forms of cleavage, namely, 6, 7, 8, 9, 10, 11, 12, it should be understood that various changes in angles and combinations of the forms shown 40 may be used. Also, in the operation of the device, one or more blades may be used, according to the contractor's judgment, based on working conditions and problems of sub-grade structure and formation.

In operation, as the device moves forward, when the reenforcement is in the rod form as shown in the drawings, the rods having been manually placed over the runners and under the blade, the blade forms the desired groove in the matrice, and deposits the tape therein. It should be understood that the tape should be treated with a non-volatile oil or grease, so that it will not adhere to the matrice after the latter has attained a mechanical set, but 55 may be easily removed therefrom.

In the event that mesh reenforcement or longitudinally extending bars are used, this type of reenforcement is laid over the runners and under the blade, guides being attached to the outward upper edges of the runners as a support to aline the reenforcement in the pavement directly behind the device.

The T shaped members or runners move 65 forward with the blade leaving the reenforcement rods or other material in alined position in the material.

It should be understood that various changes in arrangement and construction of the different members of the invention may be resorted to without departing from the spirit and intent of the following claims.

What is claimed is:

1. In a combination grooving and reinforcement supporting device, a steel blade, means for drawing the blade through unset concrete, asphalt, or like material, the top of said blade on a level with or below the surface of said material, supports for said blade, said supports resting on and guided by the side forms of the material, and runners extending parallel with the blade and aligning reenforcement material below the incision made by the blade as the latter is drawn forward.

2. In combination road building machinery, in attachment to a concrete mixer, a blade of hollow construction, a jointed tape of suitable material adapted to pass through the blade, means for feeding the tape, a template supporting the blade, said template and blade supported on the side forms of the construction whereon they are used, and means to aline and support reenforcement members below the incision made by the blade, as the device is moved over the surface of the road.

3. In a grooving device for highways and the like, a blade adapted to cleave the said highway pavement or the like, before same has mechanically set, and means to support and aline reenforcement material below the cleavage plane as the latter is formed.

4. The herein-described process of forming cleavage planes in, and reenforcing highways, pavements, floors, roofs and other like constructions, by first mechanically cleaving the material before same has attained a mechanical set, and at the same time, alining reenforcement material below the cleavage plane, and by then laying or depositing a ribbon or jointed tape in the cleavage plane, then removing said tape after the construction material has attained a mechanical set, and finally filling the cleavage plane with a filler such as asphalt, coal, or a like material.

5. A blade of hollow steel, a jointed tape, means for feeding the tape through the blade, means for supporting and guiding the blade, means for moving the blade through semi-solid or unset construction material below the finished surface thereof, and means for alining reenforcement below the cleavage plane formed by the blade before the said materials have attained a mechanical set, substantially as and for the purpose set forth.

In testimony whereof I have signed my name to this specification.
